The ornamental design for a sink basin, as shown and described.

DESCRIPTION

FIG. 1 is a top-quartering perspective view of a sink basin incorporating the principles of the present invention; FIG. 2 is a front view of the sink basin seen in FIG. 1;

FIG. 3 is a rear view of the sink basin seen in FIG. 1; FIG. 4 is a right side view of the sink basin seen in FIG. 1, the left side view being a mirror image thereof; FIG. 5 is a top plan view of the sink basin seen in FIG. 1; FIG. 6 is a bottom plan view of the sink basin seen in FIG. 1;

FIG. 7 is a sectional view, generally taken along line VII-VII, of the sink basin seen in FIG. 1;

FIG. 8 is a top-quartering perspective view of another embodiment of sink basin incorporating the principles of the present invention;

FIG. 9 is a front view of the sink basin seen in FIG. 8; FIG. 10 is a rear view of the sink basin seen in FIG. 8;

FIG. 11 is a right side view of the sink basin seen in FIG. 8, the left side view being a mirror image thereof; FIG. 12 is a top plan view of the sink basin seen in FIG. 8; FIG. 13 is a bottom plan view of the sink basin seen in FIG. 8;

FIG. 14 is a sectional view, generally taken along line XIV-XIV, of the sink basin seen in FIG. 8;

FIG. 15 is a top-quartering perspective view of another embodiment of a sink basin incorporating the principles of the present invention;

FIG. 16 is a front view of the sink basin seen in FIG. 15; FIG. 17 is a rear view of the sink basin seen in FIG. 15;

FIG. 18 is a right side view of the sink basin seen in FIG. 15, the left side view being a mirror image thereof; FIG. 19 is a top plan view of the sink basin seen in FIG. 15; FIG. 20 is a bottom plan view of the sink basin seen in FIG. 15;

FIG. 21 is a top-quartering perspective view of another embodiment of sink basin incorporating the principles of the present invention;

FIG. 22 is a front view of the sink basin seen in FIG. 21; FIG. 23 is a rear view of the sink basin seen in FIG. 21;

FIG. 24 is a right side view of the sink basin seen in FIG. 21, the left side view being a mirror image thereof; FIG. 25 is a top plan view of the sink basin seen in FIG. 21; and,

FIG. 26 is a bottom plan view of the sink basin seen in FIG. 21.

In FIGS. 15-26, the sink basin is shown with a symbolic break in its length. The appearance of any portion of the article between the break lines forms no part of the claimed
